UNITED STATES PATENT OFFICE

2,469,363

EXTERIOR BOMB CONTAINER

Harry J. Biondi, Gaithersburg, Md.

Application November 5, 1943, Serial No. 509,083

6 Claims. (Cl. 89—1.5)

(Granted under the act of March 3, 1883, as
amended April 30, 1928; 370 O. G. 757)

1

The present invention relates to exterior "bomb containers" which are preferably carried exteriorly beneath bombing aeroplanes, and usually by one point of suspension on a "bomb rack" mounted on the plane.

An arrangement of parts is provided herein which will operate when it is desired to dump or trip the whole container and its contents as a unit. This feature is common to other types of bomb containers in that the container is preferably attached at a single point of suspension to a bomb rack which is attached to the body of an aeroplane. When it is desired to discharge the container as a whole, mechanically operated cables within reach of the aviator can be used to operate the bomb rack and immediately disengage the whole container and its load of bombs from the aeroplane.

In some types of bomb containers the release of the bombs therein is accomplished by a mechanical device which is usually manually controlled and operated from an operating device within easy reach of the occupant of the aeroplane. In other types of containers the bombs are released by a push-button or other electrical device also within easy reach of the occupant of the plane.

The present invention is of the former or mechanically operated and actuated type. The modus operandi of the present type of invention will be fully explained in this specification.

The present bomb container comprises a metal shell much in the shape of a normally closed cylinder having bullet-nosed front and rear ends, and provided with two pairs of swinging hinged doors mounted beneath the container. One of the features of the present invention is an arrangement of parts which is designated the door locking and releasing mechanism, which upon proper actuation retracts the locking latches which normally hold the doors of the bomb container in closed position within the exterior outline of the container in order to avoid wind resistance as is at once understood. After the door latches are withdrawn as will be described, the doors of the container are free to drop open by gravity due to the load of bombs which they carry upon them.

As soon as all the bombs have been discharged from the container springs preferably located on the hinges of the doors act to close the same, and the automatic means provided on the door locking and releasing mechanism reverses the first operation of the latter, and the locking latches

2

are automatically replaced in engagement with the doors and securely lock them until again released by the aviator. The details of this door locking and releasing mechanism will be specifically explained at length hereinafter and is one of the major elements of the invention.

The container in hand is divided internally into two compartments, forward and aft, and each compartment is arranged to release all the bombs carried therein in one group or simultaneously. All the bombs in the second compartment may be released immediately after the first action, or can be carried indefinitely at the option of the operator in the plane. In other words, each group of bombs in the two container compartments is usually released or discharged by separate individual mechanical actuations through the door locking and releasing mechanism of the invention, as will be described fully hereinafter. However, arrangements may be made for discharging both compartments simultaneously. Other features of the device in hand will be explained as the description proceeds.

In the accompanying drawings forming part of the present specification:

Fig. 1 is a side elevation of an exterior bomb container, and the means used for mounting same on an aeroplane, and means for mechanically operating and releasing bombs from the container, with the associated parts of the aeroplane being shown in diagrammatic or phantom form.

Fig. 2 is a partial horizontal longitudinal view of the bomb container taken on line 2—2 of Fig. 1, showing levers and connecting rods associated with the unlatching or releasing of the drop doors of the container.

Fig. 3 is a transverse cross-sectional view through the bomb container taken on line 3—3 of Fig. 1, showing the container doors in open position in dotted lines.

Fig. 4 is a partial vertical sectional view taken on the line 4—4 of Fig. 3.

Fig. 5 is a partial horizontal section of the container taken on line 5—5 of Fig. 4.

Fig. 6 is a vertical cross-sectional view taken on line 6—6 of Fig. 4 showing the latch-lever and container supporting yoke details.

Fig. 7 is a detail vertical sectional view of the latch per se taken on line 7—7 of Fig. 6.

Fig. 8 is a vertical partial cross-sectional view taken on line 8—8 of Fig. 1, showing the end elevational details of the bomb rack, connections of

the container, and levers and brackets used therewith in the present invention.

In the drawings the numeral 1 indicates in exterior elevation a bomb container which comprises the subject matter of the present invention. The numeral 2 indicates in diagrammatic form the wing and associated parts of an aeroplane. Numeral 3 shows the position of the aviator; 4 is a bomb container operating device, which is connected by cable or lanyard 5 with the 10 mechanical devices 7, 8 which actuates the parts of the present invention which are arranged within the bomb container. The cable 6 operates the "bomb rack" 9, which in turn unshackles the container 1 at the point of suspension 10, when it is desired to free the whole container entirely from the aeroplane in case of emergency. The bomb rack 9 is a well known standard type of device which is not a novel part of the present invention.

The present type of bomb container is actuated and operated entirely by mechanical parts in distinction from electrically operated and actuated types of bomb containers.

The container 1, herein, comprises a drum or shell 11, preferably of metal, provided with a plurality of opposed drop doors 12, 13 etc. hinged at 14, 15 to the shell 11, of said container, and adapted to swing downwardly by gravity to take the positions 16, 17 shown dotted in Fig. 3 of the drawings. The container 1 comprises two compartments 18, 19 both of which are symmetrically arranged about the center line 20 of the container, Fig. 4. The mechanical parts of the container in both compartments 18, 19 are substantially alike, as will be seen as the specific description proceeds herein.

As the chambers 18, 19 are substantially alike, the description of the parts of one chamber will suffice for both halves of the bomb container.

The interior arrangement of the container is readily understood from Figs. 3, 4, 5 of the drawings. The shell 11, has a horizontally disposed top division wall 21, and vertical division walls 22, 23, 24, 25, 26 all connected together, as shown in Fig. 3 and supported on the walls of container 1. The doors 12, 13 are provided with horizontal parts 27, 28 properly supported by the subdivision walls 29, 30, 31, 32, and those parts provide the closure for the container 1, upon which rest the load of bombs such as 33, 34, etc. The bombs 33, 34, etc. as seen in Fig. 3 are piled in the chambers formed by the walls 22 to 26 inclusive. The compartments 18 and 19 each are provided with bungee cords 35 which are resilient, each with two substantially perpendicular branches 36, 37, and a horizontal portion 38. Vertical walls 22—26 have slots 35a in which bungee cords 35 slide. The container 1, is inverted when being loaded with bombs so the doors 12, 13 are on the top, and as the bombs 33, 34 are placed in the chambers the bungee cord is placed in tension as is readily understood and seen from Fig. 3 clearly. It is also evident that when the doors 12, and 13 are unlatched from the locking latches, 39, 39a, Fig. 4 they will be operated upon by gravity, and swing downwardly on hinges 14, 15 Fig. 3, and take positions indicated at 16, 17; and all the bombs in the container are then at once dropped or discharged therefrom by gravity, as well as by the action on the bungee cord 35 on the top of the bombs, which cord being under tension tends to shorten itself, and thus insure the complete expulsion of all the bombs in the container.

It will be seen that the locking latches 39, 39a, 75

Figs. 4 and 7, normally hold the doors 12, 13 within the outline of the container 1 and said latches are spring-pressed into extended or locking position, Fig. 4, by means of holding spring 40 mounted on the pintle 41. Spring 40 has a portion at 42 in engagement with the latch-lever 43, and another portion in engagement with pintles 44, 44 which carry the rollers 45, 45, Figs. 4 and 6 of the drawings. The latch 39 engages beneath part 46, on the doors 12 and 13 and thus holds the doors in closed positions, the latches on both ends of the doors as seen from Fig. 4 being necessary to accomplish the purpose mentioned.

The bent latch lever 43 as seen from Figs. 6 and 4, is pivotally mounted at 47 as a fulcrum in the opposed bracket angles 48, 48, which are carried on the end wall 49, of the compartment 18. The upper end 50 of latch lever 43 is also pivotally attached at point 51 to the horizontally disposed connecting rod 52. The latter rod 52 is pivotally connected to the short lever arm 53, at point 54, which last is integral with the hub 55, and short lever arm 56 of Figs. 2, 3 and 8 as shown. The hub 55 is rotatably mounted on the vertical pintle 57, which in turn is carried in bearing 58, on the top of horizontal division wall 21 of the container, and in bearing 59 formed in a recess 60 in the top-most portion of the metal shell 11 of the container 1. A lock-nut 61 secures the upper end of pintle 57 against play or movement, and a cover plate 62 is used to cover the said pintle and lock-nut as shown clearly in Figs. 3 and 4.

The cover-plate 62 is also used as a bearing plate for holding the bomb container in longitudinal alignment, in conjunction with the supporting device or hook 65 which supports the container at point 10 by means of the enclosing metal band 63, and its upstanding lugs 64, 64. The tooth or hook 65 is part of the "bomb rack" 9, which is a well known device and not a part of the present invention as before mentioned herein. From the bomb rack 9 also extends downwardly a vertically positioned holder 66 having a pair of opposed arms, 67, 67 which bear against the cover plate 62 with a reasonable amount of holding pressure but is not attached to the cover plate nor bomb container 1 at these points. It is of course apparent from Fig. 1 that there are two mechanical holding devices 66, forward and aft of the container, which cooperate with the central point of suspension devices at point 10.

The devices 7 and 8 each comprise two bent arms 68, 69, and a vertical portion 70, the latter being fastened to the aeroplane at points 71, 71. In the devices 7 and 8 also are found rotatable vertical rods 72, 72 the upper end of which can be rotated by means of cable 5 by the aviator. The lower end of rod 72 is provided with a rigidly mounted outwardly extending bent arm 73. On the pintle 57 is rigidly mounted an outwardly extending and operating arm 74 on which is carried an upstanding pin 75, adapted to engage a U-shaped recess in the end of arm 73 but not positively, and only slidably engaged therewith. The inner end of arm 74 it is seen will revolve the hub 55 and with it the short levers 53 and operate connecting rod 52. The device 8 and lever 73 then can actuate the hub 55 and connecting rod 52. In case of a discharge of the whole bomb container it is quite evident as soon as the container is "cut loose" or freed from the plane at point 10 (Fig. 1), the arms 73 are slidably disengaged from pins

75 and the whole bomb rack can be dropped as a unit from the plane.

It is evident from Fig. 2 that when lever arm 74 is moved clockwise, connecting rod 52a, latch-lever 43a and latch 39a will be operated, and the latter retracted and freed from the part 46a. And by the same actuation of lever arm 74 and simultaneously therewith the connecting rod 52, latch-lever 43 and latch 39 will be operated and the latter retracted and freed from the part 46. 10 Both these latches 39 and 39a being thus retracted the doors 12 and 13 are acted upon by gravity and drop open, and discharge all the bombs in compartment 18.

With regard to the operation of the latch 39, it is clear from what has been said that as soon as connecting rod 52 is operated towards the left (Fig. 2), by the aviator, that bent latch-levers 43 are thrown to the right or in a retracting direction at their lower ends, with reference to latches 39, and the doors 12, 13 are free to fall by gravity and the load of bombs completely discharged from the bomb container.

It is noted that spring 76 on rod 52 is compressed by the actions just described.

In connection with the connecting rods 52, it is evident the spring 76 (which abuts against adjustable collar 77 on the rod 52, and also abuts against angle 78 carried on the angle 79 of the container framework) will automatically actuate the rod 52 toward the right as seen in the right side of Fig. 2 after an unlatching operation has been performed by the aviator. As soon as the connecting rod 52 is moved to the right the top of the latch-lever 43 at point 51 also moves to the right as seen from Fig. 4, and the bottom of said latch-lever moves in the opposite direction since the lever is pivoted on fulcrum 47. This action throws the latch 39 into engagement with the part 46 (if the doors 12 and 13 in the meantime have been lifted to a closed position) and locks said doors so they are within the outline of the bomb container, since this is important due to the high rate of speed of the aeroplane as is at once understood.

The method of raising the doors 12, 13 from their opened positions 16, 17 respectively, to closed positions will be described below.

In the above case we see that it was the device 7, Fig. 1, which opened forward compartment 18 of the container 1. It is also equally evident that the device 8, Fig. 1, will operate to open aft compartment 19 of said container.

If a second cable similar to cable 5 is used to operate device 8, and cable 5 is used only for device 7, it is clear that the bombs in compartments 18 and 19 may be discharged in sequence, or in simultaneous order, or one compartment may be used and the other withheld or reserved to any desired later time for discharge purposes.

If the two devices 7 and 8 are connected by a rod 5a or if cable 5 is attached to device 8 and also to device 7, it is evident all the bombs in both compartments may be simultaneously discharged. Or if it is desired to drop the whole container and bombs therein, it is evident the cable 6 can accomplish this by the use of the bomb rack 9 and the connection at point 10, Fig. 1.

It is believed hardly necessary from what has been said to further explain the similarity of the parts in the two compartments 18 and 19, of container 1.

In connection with the raising of the doors 12, 13 from positions 16, 17 respectively shown in 75

Fig. 3 it will be noted they are closed by springs 80 preferably mounted on the hinges at 14, 15, etc., in such a manner that the load of bombs force the doors open when the latter are freed by door latches 39, 39a, etc., and as soon as all the bombs have been discharged, these springs 80 close the doors automatically whereupon the aviator permits the springs 76, 76a, Fig. 2, to come into action to operate the latches 39, 39a, etc., and lock the doors in closed positions.

Operation

Assuming that the container 1 has been loaded with bombs and mounted on the bomb rack 9, Fig. 1, and the aviator is ready to drop the bombs from compartment 18 of the container; the lanyard or cable 5 is operated which operates device 8, and its bent lever arm 13, and the operating arm 74. This operates the two latch-levers 43, 43a and latches 39 and 39a, Fig. 4, and releases doors 12 and 13. The weight of the plurality of the bombs overcomes springs 80, 80 the bungee cord 35 assists in this operation, and the load of bombs drop from said compartment 18. 15 As soon as springs 80, 80 close the doors 12, 13, the operator then "lets go" of the levers which operated cable 5, and the springs 76, 76a, act to again lock the doors 12, 13 and by means of the latches 39 and 39a. If the aviator has let go of the handle before the doors close, the doors will slam shut and push the sliding latches 39 back against the action of springs 80 as is clear from Fig. 7. If it is desired to discharge bombs in both compartments at once devices 7 and 8 must be linked together by a rod or cable 5a or otherwise connected together, so that both act simultaneously. If the compartments 18 and 19 are to be operated in sequence then the cord 5a must be actuated separately from cord 5, and attached to device 8 so that 7 and 8 will operate separately and independently as is at once seen.

The operation of bomb rack 9 is not required to be described in detail, since it is not part of the present invention, and its co-action between an 45 aeroplane and a bomb container is not novel.

From which it is seen that I have produced a novel bomb container designed to accomplish the purposes set out in this specification.

The invention described herein may be manufactured and used by or for the Government of the United States of America for governmental purposes without the payment of any royalties thereon or therefor.

I claim:

53. 1. In a bomb container, a normally closed container comprising a metal shell having a horizontal division wall and a pair of end walls thereon within the container, a pair of opposed doors hinged on the bottom of the container, means for positively locking and releasably holding said doors in a closed position, comprising a pintle mounted on the top of the horizontal division wall, a short lever revolvably mounted on the pintle, means for operating the short lever mounted on the pintle, a pivotally mounted latch-lever on the said end wall of the container, means connecting the short lever and the upper end of the latch-lever, a door latch carried by the said end division wall in slidable engagement with the lower end of the latch-lever, for the purpose of releasing the said doors, automatic means for operating the latch-lever in a reverse direction in order to lock the door latch in connection with said doors, after a bomb discharging operation has been performed, and automatic means

in engagement with the doors for closing same after a discharge of bombs, and adapted to cooperate with the locking latch, to positively lock said doors within the body outline of the container.

2. In a mechanically actuated and operated bomb container, a normally closed container having a metal shell, with a horizontal division wall and a pair of opposed end walls therein, a plurality of opposed doors hingedly mounted on the container bottom, mechanically actuated means for positively and releasably locking said doors, comprising a hub mounted on the top of said horizontal division wall, a short lever mounted on said hub, an actuating arm mounted on said hub adapted therethrough to operate said short lever, a connecting rod connected to the short lever, a latch-lever pivotally mounted on one of the end walls of the metal shell, pivotally attached to the said connecting rod, a door closing latch mounted on one of the interior end walls in slidable connection with the lower end of the latch-lever and means on the latter for normally holding the latch in locked position, and means on the doors adapted to engage the latch when said doors are in closed position, and spring means on each of the door hinges for raising the doors from open to closed position within the outline of the container, said locking means including yieldable means arranged to automatically actuate the latch-lever into a locking position with relation to the doors after the doors have been brought into a fully closed position.

3. In a mechanically actuated and operated bomb container, a normally closed container comprising a metal shell, having a horizontal division wall and a pair of end walls thereon, within the container, a pair of opposed doors hinged on the bottom of the container, mechanically actuated means for positively locking and releasably holding said doors in closed position, comprising a hub mounted on the top of the horizontal division wall, a short lever mounted on said hub, an actuating arm having an upstanding pin thereon mounted on said hub and adapted therethrough to actuate the short lever, a connecting rod connected to the short lever, a latch-lever pivotally mounted on one of the end walls of the metal shell, pivotally attached to the said connecting rod, a door locking latch mounted on one of the interior end walls of the container in slidable connection with the lower end of the latch-lever, and means on the latter for normally holding the latch in locked position, means on the doors adapted to engage the latch when said doors are in closed position, means for operating the aforesaid actuating arm through the upstanding pin

thereon comprising, a vertical rod rotatably mounted on the aeroplane, an outwardly extending bent arm rigidly mounted on said vertical rod, in operative but free and slidable connection with the upstanding pin on the said actuating arm, whereby the hub, the short arm, the connecting rod, the latch-lever and the locking latch are all operated to unlock said locking latch and release the doors of the container, and spring means on the hinges of each of the doors for automatically raising the doors to closed position after a load of bombs have been discharged from the container, and automatic means on the door locking and releasing means for relocking the door latch after the doors have been brought into closed position.

4. A device as in claim 3 in which the automatic door relocking latch means used comprises a stop angle mounted on the horizontal division wall of the container, an annular stop on the connecting rod, and a spring mounted on said rod in engagement with said stop, and with the said stop angle, adapted to actuate the latch-lever and push the door latch into a locked position beneath the doors on the container.

5. A door locking and releasing mechanism for a bomb container, comprising a pintle mounted within the container, a hub thereon, a connecting rod operatively connected with said hub, a latch-lever pivotally mounted within the container, pivotally attached to the connecting rod, a door latch mounted on the container, slidably engaged with the latch-lever, means for operating the said hub, to unlock the door latch, and automatic means on the connecting rod for operating the latch-lever and relocking the door latch, after the container doors have been brought into closed position.

6. A door locking and releasing mechanism as in claim 5 and means for operating the hub described therein comprising a revolvably mounted vertical rod, an outwardly extending bent arm rigidly mounted on the vertical rod, in operative but free slidable connection with the said pintle and hub of the container.
